UNITED STATES PATENT OFFICE.

ALBERT MAMATEY, OF NORTH BRADDOCK, PENNSYLVANIA; POTTER TITLE & TRUST COMPANY, OF PITTSBURGH, PENNSYLVANIA, A CORPORATION OF PENNSYLVANIA, ADMINISTRATOR OF SAID ALBERT MAMATEY, DECEASED, ASSIGNOR TO REMINGTON TYPEWRITER COMPANY, OF ILION, NEW YORK, A CORPORATION OF NEW YORK.

TYPEWRITER.

Application filed June 22, 1922. Serial No. 570,235.

To all whom it may concern:

Be it known that I, ALBERT MAMATEY, a citizen of the United States, residing at North Braddock, in the county of Allegheny and State of Pennsylvania, have invented a new and useful Improvement in Typewriters, of which the following is a full, clear, and exact description.

The present invention relates to type-

writers and more particularly to typewriters for writing characters requiring diacritical marks. Such languages as Czechoslovak, German, French, Swedish, Polish and Hungarian employ diacritical marks such as various accents, umlauts, etc. to a greater or less extent. Some languages employ as many as six diacritical marks which combined with the regular letters make as many as fifty characters. In accordance with my invention these languages may be written with the ordinary American typewriter keyboard without changing the letter portion thereof. The ordinary typewriter may be in accordance with my invention readily modified to write such foreign languages.

The printing of a diacritical mark over a letter should not cause any feed of the typewriter platen. In the usual form of "visible" typewriter when a key is struck the ribbon vibrator is actuated to move the ribbon under the type bar and then after the character is printed the typewriter escapement operates to feed the carriage and platen one letter space ready for the next character to be printed. In printing diacritical marks the typewriter should be arranged so that the ribbon vibrator is actuated to move the ribbon under the type bar, but the escapement should not be actuated. The diacritical mark should be printed and the platen should remain in the same place so that the letter can be then printed beneath the diacritical mark.

The present invention is illustrated as applied to the well known Remington Portable typewriter, although it will be obvious that it may be applied to other forms of typewriters to adapt them for writing foreign languages requiring diacritical marks.

In the drawings which illustrate the invention as embodied in a Remington Portable typewriter,

Figure 1 is a longitudinal section through

the typewriter illustrating a type bar, a portion of the escapement and ribbon vibrator, 55 the remainder of the machine being indicated generally in dotted lines;

Figure 2 is a detail view showing the construction as modified in accordance with my invention;

Figure 3 is a bottom plan view of a portion of the typewriter, and

Figure 4 is a skeleton perspective view showing one of the diacritical mark printing keys and its connection with the ribbon 65 vibrator.

In the drawings, the invention is shown as applied to the standard form of Remington Portable typewriter and for simplicity the greater part of the complicated mechanism thereof is omitted, the drawings being intended to illustrate the modifications made therein which embody the invention.

In the illustrated embodiment, the right hand end keys of the lower three rows of 75 the key bank are used as so-called "dead" or accent keys for printing six diacritical marks. These keys in the usual form of typewriter print account marks and fractions. The remainder of the keyboard is 80 unaffected and the remaining keys operate the typewriter mechanism in the usual manner, causing both a movement of the ribbon vibrator and the movement of the escapement. The three keys which carry the diacritical marks, however, are so arranged that while they operate the ribbon vibrator they 85 do not operate the escapement.

In Figure 1, the key 1 is one of the ordinary letter keys which operates both the 90 ribbon vibrator and the escapement. The key 1 is carried on the key lever 2 pivoted on a rod 3. The key lever is connected through the link 4 and sub-lever 5 to the type bar 6 which carries the types 7 and 8, 95 which are, respectively, the capital and lower case forms of the same letter.

The key lever 2 has a lug 9 which engages one of the fingers 10 on the universal bar 11.

The movement of the universal bar operates both the ribbon vibrator and the escapement. The universal bar 11 is carried on levers 12, one at each side of the typewriter. These levers are pivoted at points 13 at opposite sides of the typewriter and are connected by a channel bar 14, the universal 105

bar and its connected parts partaking of the fore and aft case shifting movement of the carriage and other parts that shift therewith. The operating movement of the universal bar is around its pivots 13. When the universal bar 11 is depressed, which occurs at every stroke of the normal character printing key, the channel bar 14 is given a slight rotation about the pivots 13. A link 15 is attached to the channel bar 14 by means of the usual mechanism (not shown) and serves to operate the lever 16 shown in dotted lines which operates the escapement mechanism 17 which is not shown in detail, but which is standard in this machine.

A finger 18 is carried on the channel bar 14 and operates the ribbon vibrator. When the channel bar is turned by the actuation of a key, the finger 18 engages on the under side only of the color shift bar 19 and raises it, thereby turning the lever 20 upwardly and to the rear. The motion of the lever 20 is directed to the ribbon vibrator 21 through the connecting link 22.

25 The lever 18 and the color shift bar 19 are shown in more detail in Figure 3. The color shift bar is pivoted around the axis 23, each of the pivots being indicated by such numeral in Figure 3. The color shift bar may 30 be moved in the solid line position to print black or into the dotted line position to print another color, such as red, by means of the bell crank lever 24 controlled from the color shift lever at the side of the keyboard.

35 When the color shift bar is in the position shown in solid lines, the lever 18 engages the portion 25 of the color shift bar and operates the ribbon vibrator to bring the black portion of the ribbon under the type. When 40 the color shift bar is moved to the dotted line position, the lever 18 engages the portion 26 of the color shift bar, which is nearer to its axis 23, and thereby turns the color shift bar through a greater arc around its axis 45 and moves the red half of the ribbon beneath the type bar, in case the two color ribbon is used.

A rod or rock shaft 27 extends across between the side frames of the machine and 50 carries the lever arms (not shown) which raise the padded type bar elevating rest 28, which is raised when the machine is to be used and lowered when the machine is to be packed in its case. Although this rod 55 27 is adapted to turn, it is fixed against bodily case shifting movement with the carriage and universal bar and is located directly beneath the pivots 13 of the latter.

Substantially all of the foregoing parts 60 are standard in the well known Remington Portable typewriter and no further detailed description thereof is deemed necessary as they are understood by any one skilled in the typewriter art.

65 It will be noted that the key levers bearing

the standard character keys operate the universal bar 11 to cause operation both of the ribbon vibrator and the escapement.

One of the diacritical mark, accent, or dead keys 30, its key lever 31 and the ribbon 70 vibrator connections controlled thereby in accordance with my invention are shown in detail in Figures 2, 3 and 4. The key lever 31 is pivoted to the rod 3. It is provided with the link 4 connecting it with its type 75 bar (not shown).

The finger 10 of the universal bar which would normally be engaged by the projection 9 on this key lever is, however, cut away as indicated at 40 in Figure 4, so that the 80 depression of the key lever 31 does not depress the universal bar 11 and to thereby operate the ribbon vibrator and escapement.

Since the ribbon vibrator must be operated, a special ribbon vibrating connection 85 is employed, a special lever or member to be actuated only by the diacritical mark or dead key levers and to transmit this motion to the ribbon vibrator. This special member may be made in different ways. About 90 the easiest way is to make it of sheet metal. A piece of sheet metal is bent to form a lever or member designated as a whole by the reference numeral 32. This member has forwardly and rearwardly projecting arms 95 33 and 34 respectively, connected by a channel portion 35 in the nature of a rock shaft which fits over and receives a bearing on the bar 27. The end of the lever arm 33 is turned upwardly at 36 to be engaged by 100 the three dead key levers which carry the diacritical mark keys, one of which, 31, is shown in Figure 4, and the other two of which are indicated by reference numerals 37 and 38 in Figure 3. The lever arm 34 extends beneath the color shift bar 19 close 105 beside and parallel with the finger 18 which is carried by the channel bar 14. When one of the keys bearing a diacritical mark is struck, its key lever engages the upturned end 36 of the lever arm 33 thereby turning the member 32 and raising the rearwardly 110 extending lever arm 34 which in turn engages and raises the color shift bar 19 and operates the ribbon vibrator 21 through the lever 20 and the connecting link 22. When the color shift bar 19 is in the full line position, as shown in Figure 3, the lever 34 will engage the portion 25 thereof to print 115 black characters and when the color shift bar 19 is in the dotted line position, the lever 34 will engage the portion 26 thereof to print red characters, in case a two color ribbon is employed.

Reference numeral 40 in Figure 4 indicates the cut away portion of the universal bar 19 where the fingers 10, which would normally be engaged by the key levers 31, 37 and 38, have been removed. As can readily be seen, by cutting away the fingers of 120

the universal bar beneath the key levers 31, 37 and 38, I destroy the operative connection from these levers through the universal bar to the ribbon vibrator and especially 5 the escapement mechanism. By means of the member 32 I supply a new connection between the dead key levers and the ribbon vibrator mechanism, so that the ribbon vibrator is operated but without operation of 10 the escapement.

In some forms of typewriters it is more convenient to operate the ribbon vibrator from all of the key levers by means of a special connection. In such case, the connection 15 between the universal bar and the ribbon vibrator, corresponding in function to the finger 18, is removed. Such a mechanism is shown and claimed in my co-pending application Serial No. 570,236 filed of even 20 date herewith.

In printing a letter having a diacritical mark, one of the dead keys is first struck, making the diacritical mark. Then the character key bearing the letter in question 25 is struck and the letter printed beneath the diacritical mark.

The standard parts of the machine are substantially unchanged. Substantially the only change required, aside from changing 30 the type and indices on the keys, in converting a Remington Portable typewriter, for example, to print a foreign language requiring six diacritical marks, is the cutting off of the three universal bar fingers 10 which are beneath the key levers 31, 37 and 38, and the mounting of the lever 32 to turn freely on the rod 27, the rod 27 being already in the machine.

The invention may also be employed in 40 typewriters for writing the English language or scientific symbols. By its use the diacritical marks for indicating pronunciation in English may be applied to the letters, or letters may be underlined without shifting back the typewriter carriage.

The term "diacritical mark" as employed in the claims is intended as a term of general description and not of limitation, and includes not only the diacritical marks used 50 in foreign languages but also the diacritical marks employed to indicate pronunciations in English as used in dictionaries and spelling books as well as any other mark added to a letter or character, such for example 55 as an underline, which it may be desired to have printed by the typewriter without actuation of the escapement.

While I have illustrated the invention as applied to a Remington Portable typewriter, 60 it is to be understood that the invention is

not limited in its application to such typewriter, but may be embodied in other typewriters and in other mechanisms within the scope of the following claims.

I claim:

1. In a typewriting machine, the combination of printing key levers, a pivoted universal bar operable directly by all of said key levers except one or more selected for use as dead key levers which are inoperative on the universal bar, a ribbon vibrator, escapement mechanism, actuating means controlled by said universal bar for actuating the escapement mechanism and ribbon vibrator and which permit of an actuation of the ribbon vibrator independently of said universal bar, and a member mounted to rock on a non-shifting part directly beneath the pivot of the universal bar, said member being made of sheet metal and formed with two arms one of which is operated on by the dead key lever or levers and the other of which coacts with said actuating means to move the vibrator independently of the universal bar escapement.

2. In a typewriting machine, the combination of printing key levers, a pivoted universal bar operable directly by all of said key levers except one or more selected for use as dead key levers which are inoperative on the universal bar, a ribbon vibrator, means for varying the throw of the vibrator including a hand set shiftable member, an arm on the universal bar co-operative with said hand set member to actuate the vibrator and which permits an actuation of said member and vibrator independently of said arm, escapement mechanism, means controlled by said universal bar for actuating the escapement mechanism, and a sheet metal member mounted to rock on a rock shaft and having two arms one of which is operated on by the dead key lever or levers and the other of which operates on said hand set member to actuate the vibrator.

3. A typewriter having certain standard character keys and at least one diacritical mark key, and having its universal bar cut away beneath the key lever or levers of the diacritical mark key or keys so as not to be actuated thereby, and a lever mounted on a type bar rest lever rod 27 and having an arm to be engaged by the diacritical mark key lever or levers and a second arm for engaging the color shift bar 19, substantially as described.

In testimony whereof I have hereunto set my hand.

ALBERT MAMATEY,
